UNITED STATES PATENT OFFICE.

GEORGE F. DOWNS, OF BUFFALO, NEW YORK.

OPEN-HEARTH FURNACE.

1,308,404.

Specification of Letters Patent.

Patented July 1, 1919.

Application filed March 5, 1918. Serial No. 220,454.

To all whom it may concern:

Be it known that I, GEORGE F. DOWNS, a citizen of the United States, and a resident of Buffalo, in the county of Erie and State of New York, have invented certain new and useful Improvements in Open-Hearth Furnaces; and I do hereby declare that the following is a full, clear, and exact description thereof, reference being had to the accompanying drawings, and to the letters of reference marked thereon, which form a part of this specification.

This invention relates to certain novel and useful improvements in open hearth furnaces and more particularly to improvements in the construction of the gas flues or ports of such furnaces, and consists of the matters hereinafter described and more particularly pointed out in the appended claims.

In furnaces of the kind, the gas ports, being generally made of refractory material, are subject to rapid disintegration and destruction under the action of the intense heat, necessitating frequent repairs or renewals, which are not only expensive in themselves, but interrupt the operation of the furnace, thus greatly increasing the expense. To remedy this condition, means have been provided for water-cooling such ports, but the constructions so far designed, have either had refractory linings or have had bottom walls made of refractory material. Such water-cooled ports have proved inefficient since they are gradually closed or choked up by deposits of earthy particles from the outgoing waste gases, so that after a very few days, proper operation is materially interfered with and it is necessary to delay the operation of the furnace in order to remove some of the deposits. Not only is the work of removing the deposits very laborious, but complete removal of such deposits is impossible since the deposits fuse with the refractory material of the bottom wall of the port and are in such position that the tools used for their removal are affected by the heat of the furnace and are quickly made useless.

The object of my invention is to provide a gas flue or port construction which will obviate these and other objections to water-cooled ports heretofore suggested, and which will also possess other advantages which will appear more clearly and will be

more definitely pointed out as I proceed with my specification.

In the drawings:

Figure 1 is a view representing in longitudinal section one end of an open hearth 60 furnace provided with my improvements.

Fig. 2 is a view representing a horizontal section through Fig. 1 in a plane indicated by the line 2-2 of Fig. 1.

Fig. 3 is a view representing a vertical 65 section through Fig. 1 in a plane indicated by the line 3-3 of Fig. 1.

Fig. 4 is a view representing a vertical section through Fig. 1 in a plane indicated by the line 4-4 thereof. 70

Fig. 5 is a view representing a partial section through Fig. 1 in a plane indicated by the line 5-5 thereof.

Fig. 6 is a view representing a longitudinal central section through my improved 75 flue.

Fig. 7 is a view of said flue in top plan.

Fig. 8 is a view representing a transverse section through the flue in a plane indicated by the line 8-8 of Fig. 6. 80

While the drawings show only one end of the furnace, it will be understood that the construction is duplicated at the other end.

Referring now to that embodiment of my invention illustrated in the drawings:—10 85 indicates an open-hearth furnace, and 11, the furnace chamber. (See Figs. 1 and 2.) 12 indicates the gas up-take; 13, 13, the air up-takes; 14, the gas port opening to the furnace, and 15, the air port. These parts, 90 so far as their general arrangement and construction are concerned, are familiar and need no further description.

16 indicates my improved gas port or flue, which provides the connection between the 95 gas up-take 12 and the furnace chamber 11. (See Figs. 1, 6 and 7.) Said flue is made of metal. It consists of two concentrically arranged, radially spaced, tubular members 17, 18, which are arranged with their longitudinal central axes in a line common to both, thus providing between them a jacket space or compartment 16^a, which surrounds the port or flue space defined by the inner tubular member. The flue may have a regular 105 or irregular form in cross-section, but the form illustrated is cylindrical. The jacket space 16^a is closed at both ends in any convenient manner, as by suitable heads.

The jacket space 16^a is connected, by means 110

of a pipe 19, to a source of supply of some cooling medium, as water, and by a pipe 20, to a place for discharge of the cooling medium after it has circulated through said 5 jacket space. As shown, the inlet pipe 19 terminates at the inlet opening at which it enters the jacket space, while the discharge pipe 20, is continued by an extension 20^a, to the opposite end of said jacket space. This 10 arrangement is preferred, since it compels the cooling medium to travel the full length of the jacket space before it is discharged; but the arrangement may be varied or reversed without departing from the spirit of 15 the invention, so long as a circulation of the cooling medium is produced.

The flue 16 is positioned in the gas port opening 14 of the furnace. 21 indicates the partition wall dividing the air port 15 from 20 the furnace gas port space 14. The inner end of the flue 16 terminates at the inner end of said partition wall 21 and its outer end extends well within the upper end of the gas up-take 12. The flue thus provides 25 a water-cooled, metal passageway, completely inclosing and surrounding the gas or other fuel on its way from the gas up-take 12 to the point where it joins the air entering the furnace chamber from the air 30 port 15. The word "flue," may thus be aptly used to describe the part 16 and to refer to it in its entirety and will be so used hereinafter.

It is to be noted that the inner or orifice 35 end of the flue 16 is made in a plane at right angles to the central axis of the flue. This feature of construction is important and acts to impart to the flow of gas a better or more direct discharge toward the hearth of the 40 furnace, than would be the case if it were in a vertical plane.

The water that must be depended upon for cooling purposes at steel plants, where 45 furnaces of the kind are used, is apt to contain a large amount of sediment, and I therefore provide in connection with the improved "flue," or rather with its cooling jacket-space or compartment, a cleaning device as follows: 22 indicates a pipe extending longitudinally through the jacket-space 16^a between the tubular members 17, 18, in a direction parallel to the longitudinal central axis of the "flue." Said pipe is supported beyond the "flue" within a pipe 23 50 of larger diameter, which is fixed in the outer head of the jacket-space 16^a and which rests upon or is built in the top wall of the gas up-take 12. (See Figs. 1 and 5.)

The pipe 22 projects through the end of 55 the pipe 23 and is connected to a flexible tube 25 which leads from any suitable source of air under pressure. A valve 22^a controls the supply to the pipe 22. The inner end of the pipe 22 is connected to a perforated, 60 curved nozzle pipe 26 which is located in a

plane at right angles to the longitudinal axis of the "flue" and extends, as shown, about three-quarters way around the complete perimeter of the water space or jacket.

By this construction, the pipe 22 with its 70 connected nozzle pipe 26, may be reciprocated within the jacket space 16^a, so as to bring compressed air, discharged into the pipe 22 through the flexible pipe 25 and escaping through the perforations of the 75 curved nozzle pipe 26, into forcible engagement with the walls of the jacket space throughout its length. Said pipes 22, 26, by the discharge of the air, produce an agitation of the water in the jacket space so as to dislodge any particles of solid material that may have collected, settled or have become incrusted upon, the inner faces of the walls of the jacket space, and the solid matter thus dislodged, is carried off in suspension by the 80 cooling water, as it is discharged through the pipe 20.

The importance of the cleaning device thus provided, is apparent, since an accumulation of sediment and solid matter in the 90 jacket space would soon clog and fill or choke it and prevent its operation in the manner and for the purpose intended.

From the foregoing description, it will be manifest that my improved "flue" is a separate, integral, water-cooled structure, capable of use in any open hearth furnace or other metallurgical furnace wherein its use would be desirable or necessary. It presents a complete, bare metal passageway from the 100 gas up-take to the point where the gas or fuel is to combine with the air and this bare metal passageway is completely surrounded by a cooling water jacket, which will give it the necessary protection against the intense 105 heat. Since the whole inside of the flue is water-cooled metal, the deposits of earthy particles from the outgoing gases are prevented from fusing or welding to the lower or bottom wall of the "flue". The accumulation of such deposits will thus not only be prevented or at least retarded or reduced, but, since such deposits will in any case be loose and free, they may be easily, rapidly and completely removed, with no delay in 115 the operation of the furnace.

The "flue" alone controls the flow of the gas or fuel from the time it leaves the gas up-take until it reaches the point of contact with the air, regardless of the type of construction of air-up-take and air port in the space occupied by the length of the "flue". Thus it will be readily seen that the use of my "flue" will permit many changes and modifications in the type of air up-take and air 125 port construction, which have been heretofore impossible with prior constructions of gas ports.

While in describing my invention, I have referred to certain details of mechanical con- 130

struction and arrangement of parts, it is to be understood that the invention is in no way limited thereto except as may be pointed out in the appended claims.

5 I claim as my invention:

1. In combination with an open hearth furnace of the kind described, a straight, metallic, tubular flue supported within said furnace, said flue connecting the gas uptake 10 with the interior of the furnace, means providing a jacket space entirely surrounding said flue, pipes for admitting water to, and for discharging it from, said jacket space, and a nozzle pipe in said jacket space and 15 movable lengthwise of the same from without the furnace for agitating the cooling water in said jacket space.

2. In combination with an open hearth furnace of the kind described, a straight, metallic, tubular flue supported within said furnace, said flue connecting the gas uptake 20 with the interior of the furnace, means providing a jacket space entirely surrounding said flue, pipes for admitting water to, and 25 for discharging it from, said jacket space, and a device reciprocable in said jacket space adapted to remove sediment from the jacket space walls, so that the sediment may be discharged with the cooling water from said 30 jacket space.

3. A flue of the kind described, comprising concentrically arranged inner and outer metal tubes joined at their ends to form a jacket space for a cooling medium, inlet and 35 discharge pipes for the cooling medium connected to said flue, and an agitator device terminating in a nozzle ring interposed between said tubular members and projecting beyond the outer end of said flue, said device 40 being adapted to be reciprocated within said jacket space.

4. In combination with a flue of the kind described having a cooling water jacket

space, an agitator device reciprocable in said jacket space, said agitator device consisting 45 of a pipe extending longitudinally through said jacket space and having a perforated, arcuate nozzle, the outer end of said pipe projecting beyond said flue and being adapted 50 for connection to a source of fluid under pressure.

5. In combination with a flue of the kind described having a cooling water jacket 55 space, an agitator device reciprocable in said jacket space, said agitator device consisting of a pipe extending longitudinally of said jacket space and having a curved, perforated nozzle extending about said jacket space, and means for supplying a fluid under pressure to said agitator device. 60

6. In combination with a cooling water-jacketed flue of the kind described, arranged at an angle inclined to the horizontal, pipes for admitting water to, and for discharging water from, the jacket space of said flue, 65 a mechanically operated cleaning device adapted to be reciprocated in said jacket space, and an open pipe connected to the outer end of said jacket space, forming a passageway through which the operative end 70 of said mechanically operated cleaning device projects, said pipe being arranged parallel to the longitudinal axis of the flue and extending outwardly, at the same angle of inclination, to a point spaced vertically 75 above the elevation of the cooling water discharge pipe.

In testimony that I claim the foregoing as my invention, I affix my signature in the presence of two witnesses, this 1st day of 80 March, A. D. 1918.

GEORGE F. DOWNS.
